UNITED STATES PATENT OFFICE.

LINUS J. SANDE, OF GRAND FORKS, NORTH DAKOTA.

AUTOMATIC REWINDING DEVICE FOR STENOTYPE-NOTE HOLDERS.

1,248,017.

Specification of Letters Patent.

Patented Nov. 27, 1917.

Application filed August 14, 1916. Serial No. 114,879.

To all whom it may concern:

Be it known that I, LINUS J. SANDE, a citizen of the United States, residing at Grand Forks, in the county of Grand Forks,

5 State of North Dakota, have invented certain new and useful Improvements in Automatic Rewinding Devices for Stenotype-Note Holders; and I do hereby declare the following to be a full, clear, and exact description of the invention, such as will enable others skilled in the art to which it appertains to make and use the same.

This invention relates to an automatic rewinding device and stenotype note holder.

15 In the stenotype machines used at the present time, a strip of paper is used on which the notes are made and this strip of paper is rolled from one roll to another as the notes are made. As a consequence of 20 this, the first notes are on the inside of the roll and the roll must therefore be unwound before the notes can be transcribed.

It is therefore an object of my invention to provide a device for rewinding the strip 25 of paper so that the first notes made will be the first presented for transcription.

It is a further object of my invention to provide a device wherein the strip of paper may be moved periodically a predetermined 30 distance so that the notes will be successively visible to the operator.

It is a still further object of my invention to provide a device of this character wherein in the movement of the paper will be automatic but will be manually controlled.

With these and other objects in view, such as will appear as my description progresses, my invention comprises the combination and arrangement of parts as set forth in and 40 falling within the scope of the appended claims.

In the drawing:

Figure 1 is a perspective view of a device constructed in accordance with my invention;

45 Fig. 2 is a vertical sectional view therethrough taken at right angles to the front of the casing;

Fig. 3 is a similar view taken at right angles to Fig. 2;

Fig. 4 is a section on line 4—4 of Fig. 3;

Fig. 5 is a section on line 5—5 of Fig. 3;

Fig. 6 is a detail of one of the clutches for the spools;

50 Fig. 7 is a sectional view of one of the spools;

Fig. 8 is a section on line 8—8 of Fig. 2; Fig. 9 is a section on line 9—9 of Fig. 2, and

Fig. 10 is a fragmental detail.

Fig. 11 is a detail view of one of the trunnion supporting posts.

The embodiment of the invention illustrated in the drawing includes a casing 1, the forward face 2 of which is inclined and is provided with an opening 3. A revoluble and vertically movable shaft 4 is mounted in bearings 5 which extend from the rear of the casing and secured adjacent the upper and lower ends of this shaft are beveled gears 6 and 7, respectively, while secured intermediate the ends thereof in spaced relation to each other are beveled gears 8 and 9. The gears 6 and 7 are adapted to intermesh with similar gears 10 and 11, respectively, which latter gears are secured to stub shafts 12 which are mounted in bearings 13 and in the upper and lowermost bearings 5. Secured to each of the stub shafts 12 is a plate 14 on which is a trunnion 15 and a pair of pins 16, 80 the purpose of which will later appear.

In order that the shafts 4 may be shifted vertically to cause the gears 6 and 10 or the gears 7 and 11 to intermesh, I have provided a shipper lever 17 which engages with a collar on the shaft and extends through one side of the casing and is pivoted, at 18. Mounted in bearings 19 is a shaft 20 which extends at right angles to the shaft 4 and on which a gear 21 is loosely mounted, which gear is clutched to the shaft by means of a spring pressed pawl 22 and a ratchet 23. A spring 24 is secured to the gear 21 and is adapted to rotate the same, the spring being placed under tension by means of a key 95 which is adapted to engage the end of the shaft 20. This gear 21 is so arranged that when the shaft 4 is shifted vertically it will be engaged by either the gear 8 or the gear 9 and consequently it will impart motion to the shaft 4 in the proper direction. A pair of spools 25 and 26 which include telescopic cylindrical portions 27 and flanges 28 are mounted within the casing, being supported at one end by means of trunnion 29 and at the other end by means of the trunnions 15. The pins 16 extend through openings in the adjacent flanges 28 of the spools and thus when the stub shafts 12 are rotated motion will be imparted to the spools.

105 A roller 30 is mounted in suitable plates 31 which are located adjacent the forward

face of the casing and a relatively smaller roller 32 is mounted in these plates and is slidable to and away from the roller 30 because of the presence of the slots 33 in which 5 the trunnions of the roller are mounted. Springs 34 draw the roller 32 toward and in contact with the roller 30. A detent 35 is pivoted within the casing and on a bracket, at 36, and this detent is provided 10 with a bill 37 which is adapted to engage in a notch 38 in the roller 30 and is held therein by a spring 39. A finger piece 40 extends from this detent through the forward face of the casing and by means of 15 this finger piece the bill 37 may be disengaged from the notch 38.

In operation when it is desired to rewind the strip of paper after it is taken from the stenotype machine the spool is placed 20 on the upper trunnions 15 and 29 and an empty spool is placed on the lower trunnions. The shipper lever 18 is operated to permit the engagement of the gears 7 and 25 11 and the engagement of the gear 8 with the gear 21. When the bill 37 of the 30 detent 35 is withdrawn from the notch 38 the spring 24 will operate to wind the strip of paper upon the lowermost spool 26, the paper being tightly wound thereon because of the presence of the resiliently engaged rollers 30 and 32.

Now when it is desired to transcribe the notes the shaft 4 is shifted to cause the engagement of the gears 6 and 10 and the 35 gear 9 with the gear 21. When the bill 37 is disengaged from the notch 38 and the detent released the roller 30 will revolve one complete time and the upper spool will rotate so as to wind the paper from the 40 lower spool. As soon as one revolution of the roller 30 is completed the roller will be stopped by the reengagement of the bill 37 and the notch 38 and a predetermined portion of the stenotype notes will be exhibited 45 through the opening 3 for transcription. It is to be noted that the normal tendency of the spring 24 is to rotate one or the other of the spools but this rotation is prevented by the detent 35 and because of the fact 50 that the paper is arranged in the particular manner illustrated and described, that is to say, it extends from one spool to the other and between the pair of rollers.

It will thus be seen that the strip of 55 paper on which the stenotype notes are made may be first rewound and then wound in the opposite direction predetermined distances at intervals and at the will of the operator so that the notes may be transcribed by the operator.

While I have illustrated and described a particular embodiment of my invention, it

has merely been for the sake of convenience and I do not wish to be limited to that particular embodiment as it is obvious that 65 numerous changes may be made in the details of construction without departing from the spirit of the invention or exceeding the scope of the appended claims.

The trunnions 29 are carried by posts 29' 70 to which are hingedly connected, as at 30' to the rear wall of the casing, whereby the spools 25 and 26 can be readily removed or replaced by swinging said posts. The side 75 of the casing adjacent the posts 29' is hingedly connected as at 31', whereby access can be had to the interior of the casing.

What I claim is:—

1. A winding device for stenotype note holders, comprising in combination, a casing, a vertical shaft mounted in said casing for rotative movement, a pair of stub shafts mounted at opposite ends of the vertical shaft, means for alternately gearing said stub shafts to the vertical shafts, removable trunnions mounted in the casing in alignment with the stub shafts, spools engaged between the stub shafts and the trunnions to rotate with the former, a web common to the spools, a controlling roller operated by said web and mounted parallel with said spools, said roller being positioned below the upper spool, a driving means for the vertical shaft, means to gear the driving means to drive the vertical shaft in either 95 direction, and means operative on the controlling roller to release the driving means for movement to predetermined distances.

2. A winding device for stenotype note holders, comprising in combination, a casing, a vertical shaft mounted in said casing for rotative movement, a pair of stub shafts mounted at opposite ends of the vertical shaft, means for alternately gearing said stub shafts to the vertical shafts, removable trunnions mounted in the casing in alignment with the stub shafts, spools engaged between the stub shafts and the trunnions to rotate with the former, a web common to the spools, a controlling roller operated by said web and mounted parallel with said spools, said roller being positioned below the upper spool, a driving means for the vertical shaft, and means operative on the controlling roller to release the driving means for movement to predetermined distances.

In testimony whereof, I affix my signature, in the presence of two witnesses.

LINUS J. SANDE.
